UNITED STATES PATENT OFFICE

2,508,681

CURTAIN STRETCHER

John Miele, Jersey City, N. J.

Application April 18, 1947, Serial No. 742,402

5 Claims. (Cl. 45—24)

1

The invention relates to stretchers for lace curtains, blankets and the like, of the general type in which vertical and horizontal bars extend across a rectangular frame and are shiftable with respect thereto to adjust the stretcher to proper size for any article to be stretched and dried.

The principal object of the invention is to provide a new and improved construction which permits shifting of the above mentioned bars with extreme ease and provides quickly and easily operable friction brakes for effectively holding said bars in any selected positions.

Another object is to provide a comparatively simple and durable construction which may be expeditiously manufactured and profitably sold at a reasonable price.

Figure 1 is a side elevation, partly broken away and in section.

Fig. 2 is a detail horizontal section on line 2—2 of Fig. 1.

Fig. 3 is an enlarged vertical sectional view showing a portion of the vertically shiftable curtain-anchoring bar, the carriage supporting one end of said bar, the guide track for said carriage, and the carriage brake cooperable with a portion of said track.

Fig. 4 is a detail horizontal sectional view on line 4—4 of Fig. 3.

Fig. 5 is a detail vertical section on line 5—5 of Fig. 3.

Fig. 6 is a vertical sectional view showing more particularly the carriage, track and brake means for the upper end of the horizontally shiftable curtain-anchoring bar.

Figs. 7 and 8 are sectional views on lines 7—7 and 8—8 of Fig. 6.

Fig. 9 is a detail view showing the adjusting screws with which the noses of the brake-applying cam levers are provided.

A rectangular vertically disposed frame 10 is provided, said frame having upper and lower horizontal track bars 11 and 12 and vertical track bars 13 suitably joined to the ends of said horizontal bars 11 and 12. Each of the track bars 11, 12 and 13 is of the hollow form shown more particularly in Figs. 4 and 7, and comprises an outer wall 14, two parallel side walls 15 integral with and projecting inwardly from said outer wall 14, and two angular track flanges 16 extending inwardly from the inner edges of said side wall 15, a longitudinal slot 17 being provided between said track flanges 16.

The upper track bar 11 and one of the vertical track bars 13, are provided with carding cloth

2

or the like 18 which may well be held by small channels 19 welded to said bars.

A vertically disposed curtain-anchoring member 20 extends between the upper and lower track bars 11 and 15 and the ends of said member 20 are secured to upper and lower carriages 21 and 21a which are mounted within said track bars 11 and 12 respectively; and a horizontally disposed curtain-anchoring bar 22 extends between the vertical track bars 13 and is secured at its ends to carriages 23 mounted within said track bars 13. The two curtain-holding members 20 and 22 are provided with carding cloth or the like 24 which may well be held in place by welded-on channels 25.

The carriages 21, 21a and 23 are very similar to each other in construction, and only the carriage 21 will be described in detail, reference being made more particularly to Figs. 6, 7 and 8.

20 This carriage includes an elongated one-piece body 26 extending longitudinally within the track bar 11 and having an integral downwardly projecting arm 27 near one of its ends, said arm having a narrowed portion 28 which extends 25 through the slot 17. The ends of the body 26 are provided with wheels 29 engaging the track flanges 16 of the bar 11, appropriate ball or roller bearings 30 being preferably provided for said wheels to insure extremely easy movement of the curtain-anchoring member 20. The bearings 30 surround axles for the wheels 29 and are within apertured bosses on the ends of rods screwed into threaded sockets formed in the ends of the body 26, as shown in Figure 6.

35 Between the body 26 and the outer wall 14 of the track bar 11, I provide a suitable rigid brake shoe 31 having suitably attached mounting pins 32 which extend slidably through openings 33 in the body 26, the lower ends of said mounting

40 pins having nuts or other suitable stops 34. Coil springs 35 surround the mounting pins 32, bear downwardly upon the stops 34, and bear upwardly on the carriage body 26, said springs therefore serving to lower the brake shoe 31 when permitted to do so.

45 A cam lever 36, however, is fulcrumed upon the carriage body 26 and is provided with a nose 37 cooperable with the brake shoe 31 to project the latter into tight contact with the outer wall 14 of the track bar 11, when said cam lever is forced upwardly to the position shown in the drawings. Thus, with the lever in this position, the carriage 21 is locked against movement. The lever 36 swings slightly past dead-center when swung upwardly and it will, therefore, remain in this position until pulled

downwardly by hand. Upon this latter movement of the lever, the springs 35 retract the brake shoe 31 and easy movement of the carriage 21 is therefore permitted when adjusting the curtain anchoring member 20. I preferably provide the nose 37 of lever 36 with an adjusting screw 38 for contact with the backing bar 39 of the brake shoe 31, as seen in Fig. 9. Both this screw and the backing bar are of hardened steel and, therefore, very little wear occurs, but the screw 38 is of advantage when initially adjusting the brake for most effective operation and will also be useable thereafter to compensate for any wear which occurs. A good grade of brake lining 40 is provided on the backing bar 39 for contact with the outer wall 14 of the track bar 11, and practically no wear on this lining will occur, as the movement of the carriage 21 is stopped before the brake shoe is applied to said outer wall 14.

The lower carriage 21a is almost identical with the upper carriage 21, but its arm 27a is much shorter so as not to interfere with maximum descent of the curtain anchoring bar 22. Also, the brake-actuating lever 36a of carriage 21a is of somewhat different shape to adapt it to be operated either by hand or foot. When this lever occupies the position shown in Fig. 1, the brake shoe 31a is in engagement with the outer wall of the lower track bar 12, and said shoe is released when said lever is swung upwardly.

The arms 27 and 27a of the upper and lower carriages 21 and 21a, serve as attaching means for the vertical curtain member 20. This member is preferably formed from two laterally spaced vertical bars 41 secured against opposite sides of the arms 27 and 27a and carrying the channels 25 for the carding cloth 24 of said member 20. Figs. 6 and 7 illustrate screws 42 for securing the bars 41 to the arms 27, and said bars may be fastened to the arm 27a in the same manner.

The arms 27b of the carriages 23 are disposed near the lower ends of the carriage bodies 26b and are connected with the ends of the horizontal curtain-anchoring bar 22. This bar, as seen in Figs. 3, 4 and 5, is in the form of a tube of rectangular cross-section, the arms 27b extend into the ends of this tube, and rivets or the like 42b are employed to secure said tube and arms together.

The brake shoes 31b of the carriages 23b are operable by means of levers 36b of different shape from the levers 36 and 36a, said levers 36b being suitably connected with the ends of pull cables 43 which extend throughout the greater part of their lengths within the tubular bar 22, the top of said bar, however, being formed with openings through which the end portions of the cables extend upwardly, one of these openings being shown at 44 in Fig. 3. The inner ends of the cables 43 are adjustably connected to curved links 45 which are pivoted to a hand lever 46, said hand lever being fulcrumed upon a bracket 47 suitably secured to the bar 22. When the hand lever 46 is swung to the position of Fig. 1, the links 45 pull upon the cables 43 and operate the levers 36b to engage the brake shoes 31b with the outer side walls 14 of the vertical track bars 13, thus locking bar 22 in adjusted position. When lever 46 occupies the position in question, the various pivots are slightly past dead-center relation and the lever will, therefore, remain in that position until released. When it is released, the two brake shoes 31b are released and the

bar 22 may then be vertically adjusted. The weight of this bar and its carriages 23b is preferably accurately counter-balanced by means of weights 48 connected to the upper ends of said carriages by chains or cables 49, said chains or cables extending over appropriate sheaves 50. Guide tubes 51 are preferably provided for the weights 48, said guide tubes being welded or otherwise secured to the outer sides of the track bars 13.

It will be seen from the foregoing and the accompanying drawings, that when the friction brakes are released, the vertical and horizontal curtain-anchoring bars 20 and 22 may be adjusted with ease and speed, and that said bars may be locked in any selected positions by quick and easy application of the brakes. Due to this extreme ease of operation, and the speed with which it can be performed, the attendant can accomplish a great deal more work with less fatigue than when using conventional stretchers.

Excellent results have been obtained from the general construction shown and described and it is, therefore, preferably followed. However, within the scope of the invention as claimed, numerous variations may be made.

I claim:

1. A curtain stretcher comprising a frame having horizontal upper and lower hollow track bars, and vertical hollow track bars at the ends of said hollow horizontal track bars, each of said track bars having a longitudinal slot in its inner side; horizontally shiftable wheeled carriages within said hollow upper and lower track bars; a vertical curtain-anchoring bar extending between said carriages and secured thereto; vertically shiftable wheeled carriages within said hollow vertical track bars; a horizontal curtain-anchoring bar extending between said vertically shiftable carriages and secured thereto; friction brakes mounted on all of said carriages within said hollow track bars and having brake shoes engageable with internal surfaces of the track bars; and manually operable actuating means for said brake shoes including levers pivoted to said carriages and extending through said slots of said hollow track bars, said levers having nose ends to engage said brake shoes and move to past-dead-center position to lock the shoes in braking position; one of said vertical track bars, one of said horizontal track bars, and both of said curtain anchoring bars having curtain-anchoring means.

2. In a curtain stretcher two hollow vertical track bars having longitudinal slots, wheeled carriages mounted within said hollow track bars, friction brake shoes mounted on said carriages to engage internal surfaces of said bars, spring means for retracting said brake shoes, brake shoe actuating levers pivoted to said carriages and extending through the slots of said track bars, said levers being movable to past-dead-center positions to hold said brake shoes applied, a horizontally curtain-anchoring bar extending between said track bars and connected at its ends to said carriages, a hand lever pivoted at one end of said curtain-anchoring bar, oppositely extending curved links pivoted at spaced points to said hand lever, said hollow curtain-anchoring bar having openings adjacent its ends and adjacent said hand lever, and cables having their major portions confined within said hollow curtain-anchoring bar and their end portions extending through said openings and connected to said brake shoe levers and said curved links.

3. In a curtain stretcher, spaced horizontal and vertical hollow track bars forming a rectangle, each bar having an outer wall, two parallel side walls extending inwardly from said outer wall, two track flanges extending inwardly from the inner edges of said side walls and reentrant flanges at the inner extremities of said track flanges parallel to said side walls; an elongated carriage body extending longitudinally within each hollow track bar, said body having threaded longitudinal bores at each of its ends, rods having apertured bosses at their outer extremities and threaded inner ends engaging said bores, transverse axles extending through said apertured bosses, spaced parallel wheels carried by each of said axles on opposite sides of each boss and engaging said track flanges, an elongated friction brake shoe between said body and said outer wall and cooperable with said outer wall, brake lining on the inner side of said shoe, said brake shoes having parallel mounting pins extending slidably through said body, springs surrounding said mounting pins on the outer side of said body and active thereon to retract said brake shoe, a lever mounted on said body and having a cam nose for forcing said brake shoe against said outer wall, said body having a slot through which said lever extends, and curtain-anchoring bars at right angles to each other and secured at each end to one of said bodies, the bodies of opposed parallel members being thus aligned to permit movement of their associated bars perpendicularly with respect to their associated track bars.

4. A curtain stretcher as set forth in claim 1 wherein the cams for forcing the brake shoes against their associated outer track walls each include an adjustable screw engaging a threaded bore in the cam nose and linearly movable with respect thereto to compensate for wear thereon.

5. In a curtain stretcher, a hollow track bar having an outer wall, two parallel side walls extending inwardly from said outer wall, and two angular track flanges extending inwardly from the inner edges of said side walls; an elongated carriage body extending longitudinally within said hollow track bar and having wheels at its ends engaging said track flanges, an arm integral with said body and extending therefrom at a right angle, said arm having a narrow portion between said track flanges, and a wide outer portion, a curtain-anchoring member having spaced, opposed portions to receive between them said outer portion of said arm, and means fastening said portions of said arm and said curtain-anchoring member, and a curtain-anchoring bar secured at one of its ends to said arm.

JOHN MIELE.
